US0D1015887S

(12) **United States Design Patent** (10) **Patent No.:** **US D1,015,887 S**
(45) **Date of Patent:** **** Feb. 27, 2024**

(54) **PRODUCT CONTAINER**

(71) Applicant: **Lifestyle Products, LLC**, Logan, UT (US)
(72) Inventor: **Robyn Jensen**, Hyde Park, UT (US)
(73) Assignee: **Lifestyle Products, LLC**, Logan, UT (US)

(**) Term: **15 Years**

(21) Appl. No.: **29/729,034**

(22) Filed: **Mar. 24, 2020**

(51) **LOC (14) Cl.** **09-01**
(52) **U.S. Cl.**

USPC **D9/651**; D9/430

CLAIM

The ornamental design for a product container, as shown and described.

DESCRIPTION

FIG. 1 is an isometric view of the product container in an assembled configuration;

FIG. 2 is an alternate isometric view thereof in a disassembled configuration;

FIG. 3 is a front view thereof in an assembled configuration;

FIG. 4 is a side view thereof;

FIG. 5 is a top view thereof; and,

FIG. 6 is a bottom view thereof.

The broken lines in the drawings represent portions of the product container that form no part of the claimed design.

1 Claim, 6 Drawing Sheets
